MERCURY SWITCH

Clarence E. Gehrand and Carl H. Larson, Elkhart, Ind., assignors to The Adlake Company, a corporation of Illinois

Application May 27, 1935, Serial No. 23,556

6 Claims. (Cl. 200—112)

This invention relates to mercury switches of the type disclosed in Larson Patent No. 1,967,247, in which the circuit through the switch is opened and closed by magnetically controlling the position (and hence the mercury displacement) of an iron armature in its relation to the mercury fill.

It has been found in practice that the lower buffer spring on the armature or displacer will occasionally come loose and foul the switch; and it is the principal object of this invention to eliminate this possibility. This is accomplished by employing resilient means secured in some manner to a fixed part of the switch envelope, so that not only is the switch made more certain of operation but also less power is required due to the elimination of the mercury friction that unavoidably results from carrying the lower buffer spring on the displacer.

Other and further objects will become apparent as the disclosure proceeds and the description is read in conjunction with the accompanying drawing, in which

Fig. 1 is a vertical cross-sectional view of a switch made in accordance with this invention;

Fig. 2 is a cross-sectional view taken on the line 2—2 of Fig. 1;

Figs. 3, 4 and 5 show other forms of the invention; and

Fig. 6 is a cross-sectional view of the form of the invention shown in Fig. 5, the section being taken on the line 6—6 of that figure.

It will be understood that the illustration and description of particular forms of the invention is for the purpose of disclosure only, and that the appended claims are not limited by the specific embodiments chosen unless required by the prior art.

Referring first to Fig. 1, the switch, generally designated 10, comprises a glass envelope 11, through the base of which electrodes 12 and 13 are pinch sealed. The latter electrode is substantially centrally positioned within the envelope, and is surrounded by a glass sleeve 14 to a point slightly below the top of the electrode, leaving a bare end 15 that is bent over below the top of the insulating sleeve for a purpose that is fully disclosed in Larson Patent No. 1,967,247.

The envelope contains a mercury fill 16, the level of which is controlled by an armature or displacer, generally designated 17, consisting of an iron sleeve 18 surmounting a glass sleeve 19, the latter having a slight bulge 20 near its base that serves as the seat for the iron sleeve 18 and permits the iron and glass sleeves 18 and 19 to

be held in fixed relative position by a coil spring 21, telescoped over the projecting end of the inner sleeve 19.

Movement of the displacer within the switch envelope is guided by washers 22, of hardened steel, the lower washer being positioned between the outer sleeve 18 and the bulge 20 of the inner sleeve 19, and the upper washer being clamped in place by the coil spring 21. The washers are provided with a plurality of lugs 23, that engage the walls of the envelope for maintaining the displacer in its proper axial position within the envelope.

The armature 17 is responsive to a coil 24, with which is associated an iron circuit 25, the latter being fully disclosed in the Larson Patent No. 1,967,247, making it unnecessary to describe it in detail here.

Instead of employing a lower buffer spring, as shown in the Larson patent referred to above, it has been found desirable to provide a resilient seat for the displacer at the base of the switch envelope and to have the seat secured in some manner to a fixed part of the switch. This has the advantage that it removes the buffer spring from the displacer, and consequently reduces mercury friction with a resultant saving of power in operating the switch; and it also has the distinct advantage that it cannot possibly foul the switch such as a moving spring might possibly do.

In the form of the invention shown in Fig. 1, the resilient seat consists of a coil spring 26, preferably of tungsten or molybdenum wire, the spring being placed horizontally within the envelope and having its end turns engaging the envelope wall (Fig. 2) and intermediate turns engaging the central electrode 13. The material of which this spring is composed is sufficiently resilient to protect the base of the switch envelope from damage during shipping, or from overenergization of the relay, even though it is not positioned in the manner in which coil springs are ordinarily used.

In Fig. 3 a form of the invention is shown in which the resilient seat consists of resilient wire 27, preferably tungsten or molybdenum, spiraled about the central electrode 13, and having its two ends 28 projecting laterally for engaging the displacer.

It is convenient to form the resilient seat on the central electrode prior to sealing the latter into the switch envelope, and this is done by forming spaced beads 29, 30, on the insulated electrode and then winding the wire 27 between 55

the beads to form the spring seat. After this has been done the electrode, with its spring seat, is sealed into the envelope.

It is obvious that the wire 27 may be wound on the sleeve 14 in a manner other than as shown in Fig. 3, for the laterally extending arms 28 afford sufficient resiliency to protect the base of the switch envelope.

In Fig. 4 the spring seat is a part of the electrode 12, the projecting end 31 being coiled about the central electrode and having its extreme end 32 frictionally engaging the latter electrode. Preferably the turn 33 of the coiled electrode rests on the floor of the envelope, so that stresses are not applied to the electrode 12, in a manner that may break the pinch seal. Obviously the electrode 12 may be used in a number of ways for protecting the base of the switch envelope from damage due to impact of the displacer.

In Fig. 5 a special form of spring seat is shown, which consists of a resilient clip 34, telescoped over the central electrode and having a substantially horizontal end portion 35, which forms the actual seat for the displacer. The clip 34 is also preferably of molybdenum or tungsten, these metals being sufficiently resilient to accomplish the desired purpose and having no deleterious effect on the mercury because of electro-chemical reaction.

We claim as our invention—

1. In a mercury switch of the class described, a switch envelope, a pair of spaced electrodes projecting into the envelope, a mercury fill, a magnetically responsive displacer for shifting the mercury level, one of said electrodes being substantially centrally positioned within the switch envelope and having an insulating sleeve surrounding it for a portion of its length, and resilient means held in fixed position with respect to the switch envelope by said central electrode for protecting the base of the switch envelope from damage due to impact of the displacer.

2. In a mercury switch of the class described, a switch envelope, spaced electrodes projecting into the envelope, a mercury fill, a magnetically responsive displacer for shifting the mercury level, and resilient means held in fixed position with respect to the switch envelope by one of the electrodes for cushioning downward movement of the displacer as it approaches the base of the switch envelope, said displacer when in its upper position being spaced from the resilient means.

3. In a mercury switch, a vertical switch envelope, spaced electrodes in the envelope, a mercury fill, a magnetically responsive displacer adapted to move in a vertical line within the envelope to displace more or less mercury depending on the direction of movement of the displacer, thereby to change the condition of the electrical circuit through the electrodes, a resilient element beneath the displacer for cushioning downward movement of the displacer as it approaches the bottom of the switch envelope, said

displacer when in its upper position being spaced from the resilient element, and means at the base of the envelope for anchoring the resilient element in fixed position at the lower end of the envelope whereby the resilient element as a whole is restrained from rising with the displacer when the latter is travelling upwardly with the envelope.

4. In a mercury switch, a vertical switch envelope, spaced electrodes in the envelope, a mercury fill, a magnetically responsive displacer adapted to move in a vertical line within the envelope to displace more or less mercury depending on the direction of movement of the displacer, thereby to change the condition of the electrical circuit through the electrodes, a resilient element beneath the displacer for cushioning downward movement of the displacer as it approaches the bottom of the switch envelope, said displacer when in its upper position being spaced from the resilient element, and means at the base of the envelope for anchoring the resilient element in fixed position at the lower end of the envelope whereby the resilient element as a whole is restrained from rising with the displacer when the latter is travelling upwardly with the envelope, said resilient element being formed as a part of one of said electrodes.

5. In a mercury switch of the class described, a switch envelope, spaced electrodes projecting into the envelope, a mercury fill, a magnetically responsive displacer for shifting the mercury level, and a coiled spring transversely telescoped over one of the electrodes and frictionally held thereby in fixed position with respect to the switch envelope for cushioning downward movement of the displacer as it approaches the base of the switch envelope, said displacer when in its upper position being spaced from the spring.

6. In a mercury switch, a vertical switch envelope, spaced electrodes in the envelope, a mercury fill, a magnetically responsive displacer adapted to move in a vertical line within the envelope to displace more or less mercury depending on the direction of movement of the displacer, thereby to change the condition of the electrical circuit through the electrodes, a resilient element beneath the displacer for cushioning downward movement of the displacer as it approaches the bottom of the switch envelope, said displacer when in its upper position being spaced from the resilient element, and means at the base of the envelope for anchoring the resilient element in fixed position at the lower end of the envelope whereby the resilient element as a whole is restrained from rising with the displacer when the latter is travelling upwardly with the envelope, said resilient element being frictionally telescoped over one of the electrodes and having a laterally extending buffer arm adjacent to its top.
